STORAGE DEVICE FOR THE CONTROL BARS OF BUSINESS MACHINES

David Golden, Long Beach, N. Y.

Application December 31, 1953, Serial No. 401,646

2 Claims. (Cl. 206—16)

The present invention relates to a storage means for use in connection with business machines, more particularly business machines such as accounting machines.

The operation of accounting machines and similar business machines involves the use of several exchangeable control bars as such business machines are generally designed as multiple duty machines. For instance, an accounting machine should be equipped to post a variety of different sets of accounting data such as accounts receivable, accounts payable, sales statistics etc. Each of the aforesaid sets of accounting data requires a specific and different setting of the control elements of the control bar. Accordingly, a corresponding number of appropriately set control bars must be held in readiness of which only one is used at one time.

Control bars as used in modern accounting and similar machines are heavy, unwieldy and delicate. In particular, the control elements of the bar which activate the respective control circuits in the machine, must be carefully protected from impact.

The usual practice of the machine operator is to store the control bars that are temporarily not in use in a drawer of the desk for the machine, to place them on a nearby desk or to suspend them from hooks provided for this purpose; in other words to store the control bars in whatever space is available. Obviously, such a haphazard storage of the control bars is highly undesirable. The bars are expensive, and damage to a bar is costly not only on account of repair costs but also of loss of time of the machine operator. Furthermore, a haphazard storage of the bars entails loss of time in locating the bar needed for a certain operation.

Accordingly, one of the objects of the present invention is to provide a novel box in which the control bars required for the operation of a business machine of the general type above referred to, can be conveniently stored and in which they are protected from damage.

Another object of the present invention is to provide a novel box in which the control bars are located in positions such that the more sensitive components of each bar, in particular the control elements thereof, do not touch any of the walls of the box or any other bar.

Still another object of the present invention is to provide a novel box including retaining means in which the bar can be readily inserted and which removably retain the bars in definite positions relative to each other and the walls of the box.

A further object of the present invention is to provide a novel box in which all the bars are removably held in positions such that the data strip of each bar identifying the specific operation for which the control elements of the bar are set, is conveniently visible. This affords the advantage that the operator with one glance can locate the bar needed for the desired operation.

Yet another object of the invention is to provide a box having a configuration and size such that the box can be conveniently placed upon the casing housing the mechanism of the machine in connection with which the bars are used. As a result, the bars can be placed within the convenient reach of the machine operator.

2

Another object of the invention, allied with the next preceding one, is to provide fastening means for detachably clamping the box to the casing of the machine.

Other and further objects, features and advantages of 5 the invention will be pointed out hereinafter and set forth in the appended claims forming part of the application.

In the accompanying drawing a now-preferred embodiment of the invention is shown by way of illustration and 10 not by way of limitation.

Fig. 1 is an isometric view of a storage box according to the invention mounted on an accounting machine shown in phantom.

Fig. 2 is an isometric view of the partly opened storage 15 box and of the fastening means thereof.

Fig. 3 is a fragmentary longitudinal section of the box showing the clamping means and fastening means thereof.

Fig. 4 is a section taken on line 4—4 of Fig. 3, and 20 Fig. 5 is a section taken on line 5—5 of Fig. 4.

Referring now to the figures in detail, the machine 10 shown in Fig. 1 in phantom should be visualized as an accounting machine of conventional design or a similar business machine involving the use of several control 25 bars 11 in connection with the various operations to be performed by the machine. The control bar should also be visualized as being of a conventional design. It suffices to state that the control bars have at each end a flange 11' by means of which the bars are fitted in the 30 machine, and that each bar on the side facing the operator is generally provided with a strip 12 bearing data identifying the specific operation for which the control elements of the respective bar are set. All the bars of a machine are identical, except as to the setting of the 35 control elements.

As appears from Fig. 1, the casing of the machine is rearwardly extended to provide space for the operating mechanism of the machine. This rearward extension forms a platform 10' which may be used to support the 40 storage box according to the invention which will now be described in detail.

The storage box generally designated by 13 is shown as a substantially rectangular box having a bottom part 14 and a cover 15 hinged to the bottom. The cover 45 may be latched to the bottom by a lock 16 of a design known for such purpose. A handle or grip may be provided to facilitate carrying of the closed box.

The length of the box is approximately equal to the 50 overall length of the bars, the width of the box depends upon the number of control bars for which it is designed. In extreme cases, the box may have a width equal to or greater than the length of the box. The height of the box is so selected that the side of an inserted bar facing the cover is very closely adjacent thereto or even in contact therewith to prevent appreciable up and down movements of the bars when the box is carried.

There are provided at the opposite short ends of the 55 bottom 14 two sets of retaining or clamping means generally designated by 17 and 18 respectively. The two sets of clamping means coact with each other and are generally so designed that they are capable of yieldably retaining the desired number of control bars in positions fixed relative to each other and to the walls of the box. For this purpose, each clamping means comprises a plurality of clamping members and each clamping member 60 of one set coacts with a corresponding clamping member of the other set to form a pair of clamping members for receiving and gripping the end flanges 11' of a bar 11.

Each clamping member is shown as comprising a pair 65 of springy tongues or arms 19 and 20. These tongues extend from a ledge 21 provided in the bottom of the box adjacent to the short sides thereof. The ledges may

be formed by any suitable means. In the exemplification of the invention as shown, they are formed by appropriately bent-off strips secured to the bottom and the side wall of box part 14 by any suitable means such as soldering or riveting. However, they may also be pressed out of the material of the box.

The coacting tongues 19 and 20 may be formed by a single U-piece or they may be bent out of the material of the ledge as is shown in Fig. 5.

The box and the clamping means therein may be made entirely or partly of sheet metal, plastic or any other suitable material.

As appears from Figs. 3 and 4 the end flanges 11' of the control bars when inserted between the tongues rest upon ledges 21 thereby holding the intermediate part of the control bar above the base of bottom 14. The space thus provided serves to accommodate the sensitive control elements of the bars which downwardly protrude into the said space when a bar is inserted between the tongues with its side bearing the identification strip 12 facing upwardly. As previously mentioned, the inner height of the box when closed is so that the side of the data bearing strip 12 is at a level very closely adjacent to or even in contact with the top wall of cover 15 whereby the bars are held in their positions in the clamping means.

As appears from the previous description, all the control bars when inserted in the box present their identifying data to the operator so that the operator can immediately locate with one glance the desired bar and lift the same out of the box.

The box may be placed in any position within the convenient reach of the operator. Preferably it is placed upon the rearward extension 10' of the casing of the machine. This extension generally is sufficiently wide to accommodate the box and permits placement of the box in a position very convenient to the operator.

To anchor the box in its proper position on the casing, fastening means are provided. These fastening means are shown as two arms or brackets 25. They are preferably slightly springy and may end in inwardly turned noses or hooks 25' which underlie the machine casing when snapped in position. The depending arms may be fixedly secured to the box or hinged thereto, or as shown, may extend through holes 26 in the base of box part 14 and be secured by wing nuts 27 or similar means extended through flanges of the arms. The holes 26 are spaced so that arms 25 just straddle the casing of the machine, preferably with slight tension.

The aforescribed retaining means may also be mounted directly on the machine or in another suitable location.

While the invention has been described in detail with respect to a certain now preferred example and embodiment of the invention it will be understood by those skilled in the art after understanding the invention, that various changes and modifications may be made without departing from the spirit and scope of the invention, and it is intended, therefore, to cover all such changes and modifications in the appended claims.

What is claimed as new and desired to be secured by Letters Patent is:

1. A storage case for business machine control bars of the type having a main body portion with indicia on one side for supporting a plurality of longitudinally spaced and transversely protruding control elements and having recessed flanged end portions, said case comprising a box having a rectangular bottom part with a major longitudinal axis and a minor transverse axis, a side wall at each transverse extremity of said bottom part, a cover hingedly connected to one said side wall of said box for movement between an open and a closed position, an end wall at each longitudinal extremity of said bottom part, a ledge carried by each said end wall in vertically spaced parallel relationship with said bottom wall a dis-

tance spaced above said bottom wall at least equal to the length of the transversely protruding control elements, the width of each said ledge in the longitudinal direction of said bottom wall being substantially equal to the length of said recessed flanged end portions of the bars to be stored, the longitudinal distance between the inner edges of said ledges corresponding to the length of the main body portion of said bars, a set of clamping means mounted upon the upper surface of each said ledge, each set of clamping means including a plurality of aligned spring clips, each of said spring clips comprising a pair of substantially flat parallel tongues for slidably and uniformly contacting the opposite parallel sides of said recessed ends of the control bar in full flat face engagement therewith, and fastening means including clamping arms depending from the bottom of the box and engageable with the casing of a business machine of the kind described, each of said arms comprising a substantially straight central portion, a perpendicularly outwardly extending flange at one end for securing to said bottom of said box, and a reentrant hook portion at the opposite end extending in a direction opposite to the direction of said flange and defining an acute angle with said central portion.

2. A storage case for business machine control bars of the type having a main body portion with indicia on one side for supporting a plurality of longitudinally spaced and transversely protruding control elements and having recessed flanged end portions, said case comprising a box having a rectangular bottom part with a major longitudinal axis and a minor transverse axis, a side wall at each transverse extremity of said bottom part, a cover hingedly connected to one said side wall of said box for movement between an open and a closed position, an end wall at each longitudinal extremity of said bottom part, a ledge carried by each said end wall in vertically spaced parallel relationship with said bottom wall a distance spaced above said bottom wall at least equal to the length of the transversely protruding control elements, the width of each said ledge in the longitudinal direction of said bottom wall being substantially equal to the length of said recessed flange end portions of the bars to be stored, the longitudinal distance between the inner edges of said ledges corresponding to the length of the main body portion of said bars, a set of clamping means on the upper surface of each said ledge, each set of clamping means comprising a pair of substantially flat wall surfaces for slidably and uniformly contacting the opposite parallel sides of said recessed ends of the control bar in full flat face engagement therewith, and fastening means including clamping arms depending from the bottom of the box and engageable with the casing of a business machine of the kind described, each of said arms comprising as substantially straight central portion, a perpendicularly outwardly extending flange at one end for securing to said bottom of said box, and a reentrant hook portion at the opposite end extending in a direction opposite to the direction of said flange and defining an acute angle with said central portion.
